UNITED STATES PATENT OFFICE.

ERNST SIMON, OF WERDEN-ON-THE-RUHR, GERMANY.

FUEL-FEEDING APPARATUS.

Application filed March 13, 1924. Serial No. 698,848.

To all whom it may concern:

Be it known that I, ERNST SIMON, a citizen of Germany, residing at Werden-on-the-Ruhr, in the State of Prussia, Germany, have invented certain new and useful Improvements in Fuel-Feeding Apparatus; and I do hereby declare the following to be a full, clear, and exact description of the invention, such as will enable others skilled in the art to which it appertains to make and use the same.

My invention relates to improvements in fireplaces for loose and highly inflammable fuel such as saw dust and wood shavings. The objects of the improvements are, first, to ensure a safe operation of fireplaces for fuel of the kind indicated and, second, to improve the efficiency of the combustion. With these objects in view my invention consists in feeding fuel of different character such as wood shavings and coal dust through separate passages to the fireplace or into a passage discharging into the same, means being provided for maintaining the ratio of the volumes of the said kinds of fuel constant even when changing the consumption of fuel. I have found that by thus feeding wood shavings and a suitable amount of coal dust to the fireplace the efficiency of the combustion is increased, and the coal dust, which is otherwise of minor value, is burnt in an economical way. In the practice of the invention I provide a rotary bucket wheel in the fuel supply, which wheel has the functions, first, to regulate the flow of the fuel and, second, to provide a means for closing the main part of the supply as against the fireplace, and to prevent transmission of the flame from the fireplace to the main part of the supply.

For the purpose of explaining the invention two examples embodying the same have been shown in the accompanying drawings in which the same letters of reference have been used in all the views to indicate corresponding parts. In said drawings—

Fig. 1 is an elevation showing a part of the pipe for feeding fuel to the fireplace and the bucket wheel controlling the supply of the fuel.

Fig. 2 is an elevation looking from the left in Fig. 1,

Fig. 3 is an elevation of a modification partly in section showing a part of the fireplace and the fuel feeding apparatus, and

Fig. 4 is an elevation looking from the left in Fig. 3.

In the construction shown in Figs. 1 and 2 the highly inflammable fuel such as saw dust or wood shavings is fed to the fireplace through pipes *a* and *b* connected respectively with a supply of fuel and the fireplace. The pipes *a* and *b* are connected with each other by a casing *c* of segmental section which is open at one side and has a bucket wheel *d* rotatably mounted therein. The wheel *d* and the buckets thereof are so disposed within the casing *c* and relatively to the pipes *a* and *b* that the fuel flowing downwardly through the pipe *a* falls on the buckets located at one side of the axis *e* of the wheel which is therefore rotated by the gravity of the fuel. Should the flame ignite the fuel falling through the pipe *b* it is arrested by the bucket wheel *d* and deflected thereby into the outer air, so that it does not ignite the fuel within the pipe *a*. The axis *e* carries a registering apparatus *f* showing the amount of fuel flowing through the pipe *b*.

In the modification shown in Figs. 3 and 4 the wood shavings fall through the pipe *a'*, the case *c'* and the pipe *b'* into a fireplace. To the pipe *b'* a pipe *h* is connected, by means of which coal dust is passed from a tank *g* to the pipe *b'*, the supply of coal dust being controlled by means of a screw conveyer *i* carrying the coal from the bottom of the tank to the top end of the pipe *h*. The axis *k* of the screw conveyer is connected with the axis *e* of the bucket wheel *d'* by a belt gearing *m* or the like, so that the amount of coal dust corresponds to the amount of fuel supplied through the pipe *a*.

While in describing the invention reference has been made to particular examples embodying the same, I wish it to be understood that I do not limit myself to the constructions shown in the drawings and that various changes may be made in the general arrangement of the apparatus and the construction of its parts without departing from the invention. For example, I do not limit myself to the construction of the means for regulating the supply of coal dust in accordance with the supply of wood shavings shown in Figs. 3 and 4.

I claim:

1. The combination, with a fireplace, of a downwardly directed pipe for supplying

fuel to said fireplace, a casing open at one side included in said pipe, and rotary vanes within said casing in position for being operated by the fuel falling through said pipe 5 and closed side of the casing.

2. The combination, with a fireplace, of a downwardly directed pipe for supplying fuel to said fireplace, a casing open at one side included in said pipe, and a rotary 10 bucket wheel mounted within said casing so that the buckets at one side of its axis and on the closed side of the casing are struck by the fuel falling through said pipes.

15 3. The combination, with a fireplace, of a downwardly directed pipe for supplying fuel to said fireplace, a casing open at one side included in said pipe, rotary vanes within said casing in position for being 20 operated by the fuel falling through said pipe and the closed side of the casing, and registering mechanism connected with said rotary vanes.

4. The combination, with a fireplace, of 25 a downwardly directed pipe for supplying fuel to said fireplace, a casing open at one side included in said pipe, a rotary bucket wheel mounted within said casing so that the buckets at one side of its axis and on

the closed side of the casing are struck by 30 the fuel falling through said pipes, a second fuel supply, and means connected with said bucket wheel for regulating the supply of fuel through said second fuel supply.

5. The combination with a fireplace, of a 35 downwardly directed pipe for supplying fuel to said fireplace, a casing open at one side and in communication with said pipe, and a rotary wheel within said casing and having the vanes on one side intersecting the pipe, and the vanes on the other side open to the atmosphere.

40 6. The combination with a fireplace, of a downwardly directed pipe for supplying fuel to said fireplace, a casing open at one side and included in said pipe, and a rotary wheel mounted within the casing and having vanes on one side in line with the passage of the fuel through the pipe, and the vanes on the other side extending out 45 through the open side of the casing, and a fuel supply pipe connected to the first mentioned pipe and having a fuel feeding mechanism connected with and driven by the rotary vanes.

50 In testimony whereof I hereunto affix my signature.

55 ERNST SIMON.
